CLARENCE RENSHAW, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

SWITCHING DEVICE.

1,181,250.

Specification of Letters Patent.

Patented May 2, 1916.

Application filed April 24, 1913. Serial No. 763,276.

To all whom it may concern:

Be it known that I, CLARENCE RENSHAW, a citizen of the United States, and a resident of Edgewood Park, in the county of Allegheny and State of Pennsylvania, have invented a new and useful Improvement in Switching Devices, of which the following is a specification.

My invention relates to switching devices for electrical apparatus, and it has special reference to flexible shunts employed in connection therewith.

The object of my invention is to provide a flexible shunt of the multi-ribbon type having one or more thin conducting strips interposed between the adjacent ends of the ribbons for effecting intimate contact between them and for carrying a portion of the current to the member to which the shunt is attached.

Heretofore, multi-strand flexible shunts have been employed for connecting the movable contact members to a stationary portion of a switching device, but, in cases where the several strands comprised braided copper ribbons, excessive heating resulted at the point of connection by reason of poor electrical contact between the uneven surfaces of the several adjacent members.

It is my purpose to obviate the difficulties heretofore encountered in electrical apparatus of this type, and to provide effective means, which shall be simple and inexpensive to assemble, for improving the electrical connections and carrying a portion of the current.

According to my invention, I provide one or more thin U-shaped conducting clips which are disposed over the ends of a portion, or all, of the several ribbons of the shunt, in such manner as to provide a portion of one of said clips intermediate the adjacent ribbons. The clips may also be advantageously arranged so that one side thereof shall be interposed between the shunt and the contact surface to which it is secured.

My invention is illustrated in the accompanying drawing in which—

Figure 1 is a view, partially in section and partially in side elevation, of a switching device embodying a flexible shunt constructed in accordance with my invention, Fig. 2 is a perspective view of an end of the shunt shown in Fig. 1; Figs. 3, 4 and 5 are views in end elevation of shunts embodying modified forms of my invention.

Referring to Figs. 1 and 2, the apparatus here shown comprises a stationary contact member 1, a movable contact member 2 for coöperating therewith, a plurality of arcing contact terminals 3, respectively associated with said contact members, and a stationary bracket 4 to which a movable intermediate member 5 is pivotally connected by a pin 6, the member 5 serving as a support for a conducting member 7 which has a pivotal connection therewith, through the agency of a pin 8. The member 7 carries the movable contact member 2 and is provided with a projecting portion 9 having a contact surface 10 to which one end 11 of a flexible multi-ribbon shunt 12 is attached by means of suitable bolts 13 and washers 14, in a well known manner. The other end 15 of the shunt 12 is similarly secured to a contact surface 16 which forms a part of the stationary bracket 4.

An inclosing casing 17 surrounds the component parts of the switching device hereinbefore described and the stationary contact member 1 is secured thereto by means of a supporting bracket 18 of conducting material having an integral stud 18^a which projects through the casing 17 and serves as one terminal of the device. A stud 19, which forms an integral part of the conducting bracket 4, constitutes the other terminal.

Between the lug 20 on the bracket 4 and a portion 21 of the member 7, a coil spring 22 is disposed for the purpose of moving the contact member 2 away from its coöperating stationary member 1 when released.

The shunt 12 comprises a plurality of rib-

bon conductors 23 of copper braid or other suitable conducting material such as is commonly employed for this purpose. A plurality of U-shaped conducting clips 24 are 5 placed over the ends of certain of the ribbons to insure that a portion of some one of the clips is interposed between the adjacent surfaces of the several conductors 23. As shown in Figs. 1 and 2, conducting clips 24 10 respectively envelop the ends of the two outer ribbons 23, so that a portion of each of the clips is located on the outside of an outer ribbon. A relatively large clip 25 is placed over each entire end portion of the 15 shunt 12 and has one of its side portions interposed between a side portion of one of the smaller clips 24 and the conducting surfaces 10 and 16, respectively, while the other side portion thereof lies between the other 20 clip 24 and the clamping washers 14.

By means of the bolts 13, any desired pressure may be exerted on the ribbons 23 and clips 24 and 25, whereby intimate electrical contact between the component parts 25 may be secured. Furthermore, a portion of the current conducted by the several ribbons 23 is conducted to the contact surface 10 of the member 7 through the conducting clips 24 and 25, whereby excessive heating 30 is prevented.

Referring now to Fig. 3, a plurality of conducting clips 27, 28 and 29 are employed, one arm of each clip being placed adjacent to the contact surface 10 and the other arms 35 of the clips being respectively disposed in contact with the several conducting ribbons 23 which constitute the shunt 12.

In Fig. 4, clips 29 envelop the ends of the outside ribbons 23, while clips 30 span the 40 ends of the two outside ribbons 23 and make electrical contact, the one with the other, between the inside ribbons.

The modified form shown in Fig. 5 comprises a plurality of clips 24 which severally 45 envelop the ends of the component ribbons 23 and make electrical contact, the one with the other, to effect the desired results.

These and other modifications of my invention, which may be made without departing 50 from the spirit and scope thereof, are intended to be covered by the appended claims. Furthermore, I do not wish to be restricted to any particular type of switching device.

55 The device illustrated and described is intended to be merely one example of many to which my invention is applicable.

I claim as my invention:

60 1. A flexible shunt comprising a plurality of superimposed ribbon conductors, and a plurality of thin conducting strips interposed between the ends thereof.

2. A flexible shunt comprising a plurality

of superimposed ribbon conductors, and a plurality of U-shaped conducting strips disposed over the ends of certain of said conductors. 65

3. A flexible shunt comprising a plurality of superimposed braided copper ribbons, and conducting clips spanning certain of the end 70 portions of said ribbons.

4. A flexible shunt comprising a plurality of superimposed thin conductors, and a plurality of U-shaped conducting members in intimate contact therewith. 75

5. A flexible shunt comprising a plurality of superimposed braided conducting ribbons, and means interposed between the ends of said ribbons for effecting good electrical contact between adjacent ribbons. 80

6. The combination with a conducting member, and a flexible multi-ribbon shunt attached thereto, of a plurality of thin conducting strips interposed between said ribbons and adjacent to said conducting member at the point of attachment. 85

7. The combination with a conducting member having a contact surface, and a plurality of superimposed flexible shunts, of a plurality of conducting strips disposed adjacent to said contact surface and in intimate contact with portions of said shunts, and means for clamping said parts tightly to the contact surface of said conducting member. 95

8. The combination with a shunt of flexible ribbons, a conducting member, and means for clamping said ribbons thereto, of a plurality of strips of conducting material, one end of each strip being interposed between the ends of said ribbons and the other end lying adjacent to said conducting member, for effecting good electrical contact between adjacent ribbons and also for carrying current to said conducting member. 100

9. The combination with a conducting member, of a multi-ribbon flexible shunt for said member having U-shaped conducting strips in intimate contact with the ends thereof and partially interposed between the adjacent ribbons for assisting to conduct current. 110

10. A multi-strand flexible shunt having U-shaped clips disposed over the end portions of certain strands and relatively large 115 clips enveloping all of said strands and the smaller clips.

11. A multi-ribbon flexible shunt having a plurality of U-shaped clips severally disposed over the ends of the ribbons in side-by-side relation and in intimate contact with one another. 120

12. A flexible shunt comprising a plurality of superimposed ribbon conductors, a plurality of U-shaped clips disposed over the 125 ends of the respective outside conductors,

and a plurality of larger and similar clips disposed over the ends of correspondingly-located conductors constituting the respective halves of said shunt, said last named 5 clips being in mutual electrical engagement.

13. A flexible shunt comprising a plurality of superimposed braided conducting ribbons, and a thin conducting strip interposed between said ribbons.

10 14. A flexible shunt comprising a plurality of superimposed conducting ribbons, and

conducting means interposed between adjacent ribbons and in intimate electrical engagement therewith.

In testimony whereof, I have hereunto 15 subscribed my name this 17th day of April, 1913.

CLARENCE RENSHAW.
